UNITED STATES PATENT OFFICE.

CHARLES F. SMITH, ARTHUR C. THIELE, AND LLOYD P. WALKER, OF MILWAUKEE, WISCONSIN, ASSIGNORS TO SMITH ENGINEERING WORKS, OF MILWAUKEE, WISCONSIN, A CORPORATION OF WISCONSIN.

CONICAL CRUSHING MILL.

Application filed May 21, 1926. Serial No. 110,684.

Our invention relates to a crushing device and particularly to a cone crusher wherein a generally conical concave is rotated about a single generally conic crushing roll. 5 One object of our invention is to provide a roll crusher of the type herein shown wherein rock of relatively large size may be taken without serious strain on the machine. Another object is the provision of such a 10 crusher wherein the rock is reduced in a series of pinches. Another object is the provision of improved feeding means for such a crusher. Another object is the provision of an improved adjustment for such 15 a crusher. Another object is the provision of improved driving and bearing means. Other objects will appear from time to time in the course of the specification and claims.

We illustrate our invention more or less 20 diagrammatically in the accompanying drawings, wherein—

Figure 1 is a plan view;

Figure 2 is a section on the line 2—2 of Fig. 1;

25 Figure 3 is an end elevation of one end; Figure 4 is an end elevation of the opposite end; and

Figure 5 is a detail section on the line 5—5 of Fig. 4.

30 Like parts are indicated by like symbols throughout the specification and drawings.

A generally indicates a base member having at one end the upwardly projecting portion A¹, at the opposite end a relatively low 35 portion A², and an intermediate portion or step A³.

Mounted on the portion A¹ is a supporting member B upwardly projecting from the sides of which are the bearing members 40 B¹ wherein is trunnioned the supporting bearing ring B² by the trunnions B³. B⁴ is an upwardly projecting support member associated with the member B and being provided with the upwardly projecting members B⁵ in each of which are mounted apertured bearing blocks B⁶ adjustable for example by means of the shims B⁷. B⁸ is a cap or cover adapted to be held by the screws B⁹, and B¹⁰ are jack screws for raising the bearing blocks to insert or remove shims.

Trunnioned in the blocks B⁶ is the bearing sleeve C having the trunnions C¹. It is pro-

vided with the inner bearing member C² of Babbitt metal or other suitable material apertured in line with the oiling duct C³ controlled by the oiling compression member C⁴. C⁵ is a terminal closure cap externally screw threaded as at C⁶ in engagement with the end C⁷ of the sleeve C and apertured as at C⁸ to receive the locking screws C⁹ which penetrate the sleeve as at C¹⁰. C¹¹ is any suitable closure or cover plate for the end of the member C⁵. C¹² is a guard plate provided for example with the packing C¹³, and secured to the opposite end of the sleeve C.

55 Mounted in the bearing sleeve B² is the conical apertured crushing concave D. Interposed between them may be any suitable wear taking portion D¹. D² is any suitable locking member or ring secured to the inner end of the concave D as by the screws D³, serving to lock it about the bearing ring B². Mounted about the intermediate portion of the concave D is the driving gear 60 D⁴ in mesh with the pinion D⁵ upon any suitable drive shaft D⁶ the power source for which is not herein indicated and forms no part hereof. D⁷ is any suitable driving pulley, the shaft being mounted for example 65 in the bearings D⁸. The crushing concave D has a conical lining member D⁹ which is provided with a flange D¹⁰ and is secured to the crushing concave D by screws D¹¹.

70 Mounted about the large end of the concave is any suitable wear taking track E of relatively resistant material, for example manganese steel, adapted to oppose or rest upon the two rollers E¹ pivoted upon the movable blocks E² upon the base portion 75 A³, such portion being slotted for example as at E³ to receive a downwardly projecting slide or guide member E⁴ upon such blocks E². E⁵ are controlling set screws adapted to engage the outer faces of such blocks, 80 to provide for their lateral adjustment toward and away from each other.

85 G is any suitable scraping member or blade mounted for example upon the shaft or rod G¹ one end of which is pivoted as at G² to the member C¹² attached to the inner end of the bearing sleeve C. The opposite end of the shaft is slidably secured in the 90 end of the arms G³ the connection for which

will be below described. It is provided with a terminal stop member G^4 adapted to engage the outside of the end of the arm G^3 . G^5 is a stop on the rod G^1 and G^6 a compression spring adapted normally to thrust the rod G^1 to the left, as shown in Figure 2 in order to hold the block G^4 normally in contact with the outer face of the supporting arm or bracket G^3 . The spring G^6 10 acts also as a torsional spring with a left hand movement in order to hold the scraping blade G in contact with the inner surface of the conical lining member D^9 .

Mounted upon the support member A^2 is 15 any suitable upwardly projecting bracket having the two verticals H^1 H^2 connected by the upper transverse member H^1 . Projecting upwardly from the member H^1 are the two arms H^2 provided with the bearing blocks H^3 resting upon the removable adjusting shims H^4 . H^5 are jack screws for raising the bearing blocks for insertion or removal of the shims. H^6 is a bearing sleeve provided with the trunnions H^7 rotatable in 20 the blocks H^3 . It contains the wear taking bearing member H^8 , of babbitt or other suitable material, apertured as at H^9 in line with the oil aperture H^{10} and the oil compression members H^{11} . H^{12} is a closing cap for the 25 outer end of the sleeve and H^{13} a shield for the inner end of the sleeve provided with the packing means H^{14} .

Depending from said sleeve H^6 and pivoted to it as at I is the link I^1 to the bottom 30 of which is secured the transverse yoke I^2 held by the locking nuts I^3 screw threaded upon the lower end of the link I^1 . The yoke I^2 is provided with the centering members I^4 in opposition to the centering members I^5 on the transverse frame member H^1 . Between them are compressed the spiral springs I^6 adapted normally to draw the bearing sleeve H^6 downwardly.

The supporting bracket G^3 for the rod G^1 45 is preferably secured to the upwardly projecting members H^2 . The sleeves C and H^6 are generally aligned and rotatably receive the opposite ends of the crusher shaft generally indicated as K . Such shaft includes the reduced end sections K^1 to engage said sleeves respectively, the intermediate sections K^2 and the relatively enlarged central section K^3 with the outwardly projecting flange K^4 upon which is seated the conical crushing 50 head K^5 . Such head is provided with a removable crushing mantle K^6 bearing upon an intermediate layer, for example of zinc K^7 . The mantle is provided with lugs K^8 adapted to penetrate cam slots K^9 in the 55 conic head, and then be rotated so that lugs K^8 ride upon cam surfaces K^{10} to draw the mantle tight on the head.

Mounted upon the bearing ring B^2 , as by 60 the bracket L is the enlarged feed chute L^1

in communication with the pivot spout L^2 65 extending within the small end opening of the concave D to a point upon the feed or receiving side of the roll.

It will be realized that whereas we have 70 described and shown a practical and operative device that nevertheless many changes may be made without departing from the spirit of our invention, and we therefore wish our drawings and description to be taken as in a broad sense illustrative and 75 diagrammatic rather than as limiting us to our precise showing.

The use and operation of our invention are as follows:

We provide a crushing concave adapted 80 to be rotated about a generally horizontal axis. The concave is shown as a relatively short flared roll one end of which is rotatably received in a trunnioned external ring bearing B^2 , the other end being provided with the bearing track E resting upon a pair of rollers E^1 . The concave is positively driven by means of the surrounding gear D^4 in mesh with the pinion D^5 . The trunnioned bearing B^2 permits adjustment of the 85 supporting rollers E^1 , and these rollers may be adjusted toward or away from each other, in order to allow for wear, or to control the angle or slope of the concave.

Mounted within the open ended concave 90 member is the crushing shaft K one end of which is mounted in the trunnioned bearing sleeve C and the other in the trunnioned and yieldably mounted sleeve H^6 . The spiral springs I^6 , thrusting downwardly upon the 95 yokes I^2 , tend to draw the bearing and thus the shaft downwardly in relation to the concave. The cone K^5 and the crushing mantle K^6 are thus thrust downwardly into contact 100 with the lower portion of the concave.

In operation material is fed to the device 105 through the hopper L^1 and is delivered from the inner end of the chute L^2 to the crushing zone between the cone or roller and the concave. As the concave is rotated and as the roller is compressed against it, the roller or cone rotates in response to the contact. The material is fed to the point of entry between roll and concave, so that in response to free 110 rotation, it is crushed or nipped between them. The concave is driven at a rapid rate, sufficient to maintain a substantial proportion, if not all, of the material being crushed in centrifugal contact with its inner surface 115 as it rotates. We therefore provide a scraper G to scrape the material from the surface of the concave, to prevent packing. The scraper operates to separate the crushed material to throw it back for re-crushing, incidentally breaking up such clods or portions 120 as tend to pack.

We claim:

1. A conical crushing mill comprising a

- 5 rotatably mounted conical concave and a 65 conical crushing head within the concave with its axis at an angle to the axis of the concave, a shaft for such head, a pivotal support for such shaft positioned beyond one end of the concave and a yieldingly mounted support for the opposite end of the shaft positioned beyond the opposite end of the concave.
- 10 2. A conical crushing mill comprising a 70 rotatably mounted conical concave and a conical crushing head within the concave with its axis at an angle to the axis of the concave, a shaft for such head, the ends of 75 said shaft projecting outwardly beyond the opposite ends of the concave, and bearings therefor, situated beyond the ends of the concave.
- 15 3. A conical crushing mill comprising a 80 rotatably mounted conical concave and a conical crushing head within the concave with its axis at an angle to the axis of the concave, a shaft for such head, including a pivoted bearing for the end of said shaft 85 beyond the feed end of the concave and a yieldably mounted bearing for the opposite end of the shaft.
- 20 4. A conical crushing mill comprising a 90 rotatably mounted conical concave and a conical crushing head within the concave with its axis at an angle to the axis of the concave, a shaft for such head, including a pivoted vertically adjustable bearing for the end of said shaft beyond the feed end of the 95 concave and a yieldably mounted bearing for the opposite end of the shaft.
- 25 5. A conical crushing mill comprising a 100 rotatably mounted conical concave and a conical crushing head within the concave with its axis at an angle to the axis of the concave, a shaft for such head, a pivotal support for such shaft positioned beyond one end of the concave and a yieldingly mounted support for the opposite end of the 105 shaft positioned beyond the opposite end of the concave, and means for axially adjusting said shaft.
- 30 6. A conical crushing mill comprising a 110 rotatably mounted conical concave, a trunnioned bearing ring therefor, a conical crushing head within the concave, its axis at an angle to the axis of the concave, and supporting means for limiting the rotation of said concave about the axis of the bearing ring.
- 35 7. A conical crushing mill comprising a 115 rotatably mounted conical concave and a conical crushing head within the concave with its axis at an angle to the axis of the concave, means for rotating said concave, and supporting bearing means for such concave including in part a plurality of laterally spaced supporting rollers.
- 40 8. A conical crushing mill comprising a 120 rotatably mounted conical concave and a 70 conical crushing head within the concave with its axis at an angle to the axis of the concave, means for rotating said concave, and supporting bearing means for such concave including in part a plurality of laterally spaced supporting rollers, and a removable wear taking track about said concave opposed to said rollers.
- 45 9. A conical crushing mill comprising a 80 rotatably mounted conical concave and a 85 conical crushing head within the concave with its axis at an angle to the axis of the concave, means for rotating said concave, and supporting bearing means for such concave including in part a plurality of laterally spaced supporting rollers, and means for laterally adjusting such rollers.
- 50 10. A conical crushing mill comprising a 95 rotatably mounted conical concave and means for rotating it, a conical crushing 100 head within the concave, a supporting bearing about one end of said concave, and a supporting roller positioned beneath the opposite end of said concave.
- 55 11. A conical crushing mill comprising a 105 rotatably mounted conical concave and means for rotating it, a conical crushing head within the concave, a tiltably mounted supporting bearing about one end of said concave, and an adjustable supporting bearing means beneath the opposite end of the concave.
- 60 12. A conical crushing mill comprising a 110 rotatably mounted conical concave and means for rotating it, a conical crushing 100 head within the concave, a tiltably mounted supporting bearing about one end of said concave, and an adjustable supporting bearing means beneath the opposite end of the concave, including in part a plurality of 105 supporting rollers.
- 65 13. A conical crushing mill comprising a 115 rotatably mounted conical concave and means for rotating it, a conical crushing head within the concave, a tiltably mounted supporting bearing about one end of said concave and an adjustable supporting bearing means beneath the opposite end of the concave, including a pair of supporting 120 rollers and means for varying the distance therebetween.
- 70 14. A conical crushing mill comprising a 125 rotatably mounted conical concave, a conical crushing head within the concave, a tiltably mounted supporting bearing about one end of said concave, and an adjustable supporting bearing means beneath the opposite end of the concave, a gear about said concave, a gear in mesh therewith, and means for driving said last mentioned gear to rotate the concave.
- 75 15. A conical crushing mill comprising a 130 rotatably mounted conical concave and a

- conical crushing head within the concave, a shaft for such head, a pivotal support for such shaft positioned beyond the line of the concave and a yieldingly mounted support 5 for the opposite end of the shaft, and means for vertically adjusting said first mentioned support.
16. A conical crushing mill comprising a rotatably mounted conical concave and a 10 conical crushing head within the concave, a shaft for such head, a pivotal support for such shaft positioned beyond the line of the concave, comprising a fixed, upwardly projecting support member, a plurality of vertically adjustable members mounted thereon, removable adjustment shims for said members, a tilttable bearing member for the end of said shaft and a pivotal connection between it and said members.
17. A conical crushing mill comprising a 15 rotatably mounted conical concave and a conical crushing head within the concave, a shaft for such head, a pivotal support for such shaft positioned beyond the line of the concave and a yieldingly mounted support for the opposite end of the shaft, including a fixed upwardly projecting support member, a vertically movable support member associated therewith, a bearing sleeve for the shaft associated with the upper end thereof, and yielding means tending normally to move such movable support member downwardly.
18. A conical crushing mill comprising a 20 rotatably mounted conical concave and a conical crushing head within the concave, a shaft for such head, a pivotal support for such shaft positioned beyond the line of the concave and a yieldingly mounted support for the opposite end of the shaft, including a fixed upwardly projecting support member, a vertically movable support member associated therewith, a bearing sleeve for the shaft associated with the upper end thereof, and yielding means tending normally to move such movable support member downwardly.
19. A conical crushing mill comprising a 25 rotatably mounted conical concave and a conical crushing head within the concave, a shaft for such head, a pivotal support for such shaft positioned beyond the line of the concave and a yieldingly mounted support for the opposite end of the shaft, including a fixed upwardly projecting support member, a vertically movable support member associated therewith, a bearing sleeve for the shaft associated with the upper end thereof, and yielding means tending normally to move such movable support member downwardly, comprising a yoke on such member and a plurality of springs compressed between such yoke and the fixed support member.
20. A conical crushing mill comprising a 30 rotatably mounted conical concave and a conical crushing head within the concave, a shaft for such head, a pivotal support for such shaft positioned beyond the line of the concave and a yieldingly mounted support for the opposite end of the shaft, including a fixed upwardly projecting support member, a vertically movable support member associated therewith, a bearing sleeve for the shaft associated with the upper end thereof, and yielding means tending normally to move such movable support member downwardly, and a plurality of vertically adjustable pivot members associated with such bearing sleeve.
21. A conical crushing mill comprising a 35 rotatably mounted conical concave and a conical crushing head within the concave, a shaft for such head, a pivotal support for such shaft positioned beyond the line of the concave and a yieldingly mounted support for the opposite end of the shaft, including a fixed upwardly projecting support member, a vertically movable support member associated therewith, a bearing sleeve for the shaft associated with the upper end thereof, and yielding means tending normally to move such movable support member downwardly, and a plurality of vertically adjustable pivot members associated with such bearing sleeve; comprising pivot blocks and adjusting shims associated therewith.
22. A conical crushing mill comprising a 40 rotatably mounted conical concave and a conical crushing head within the concave, and a scraper adapted to clear material from the inner face of said concave along a zone spaced away from and above the crushing zone between the head and the opposed portion of the concave and supporting means engaging each end of said scraper.
23. A conical crushing mill comprising a 45 rotatably mounted conical concave and a conical crushing head within the concave, and a scraper adapted to clear material from the inner face of said concave along a zone spaced away from and above the crushing zone between the head and the opposed portion of the concave, a rotatably mounted supporting member for said scraper, and means for rotating it and for thereby normally engaging the scraper with the opposed face of the concave, said means including a fixed abutment, an abutment on the scraper, and a coil spring interposed therebetween.
24. A conical crushing mill comprising a 50 rotatably mounted conical concave and a conical crushing head within the concave, supports for each end of said head posi-

tioned beyond the ends of the concave, a scraper adapted to clear material from the inner face of said concave and supporting connections between the ends of said 5 scraper and the supports for the crushing head.

25. A conical crushing mill comprising a rotatably mounted conical concave and a conical crushing head within the concave, 10 supports for each end of said head, a scraper adapted to clear material from the inner face of said concave and supporting connections between the ends of said scraper and the supports for the crushing head.

15 26. A conical crushing mill comprising a rotatably mounted conical concave and a conical crushing head within the concave, such crushing head being positioned to oppose the lower portion of the concave, a 20 scraper positioned within said concave to clear material from the upper portion of said concave, supports for each end of the crushing head, a scraper supporting arm extending upwardly from one of said supports, 25 the other of said supports being apertured to admit the opposite end of the scraper.

27. A conical crushing mill comprising a rotatably mounted conical concave and a conical crushing head within the concave, 30 such crushing head being positioned to oppose the lower portion of the concave, a scraper positioned within said concave to clear material from the upper portion of said concave, and supporting members, at the 35 opposite ends of said concave, adapted to support the ends of the scraper and of the crushing head.

28. A conical crushing mill comprising a 40 rotatably mounted conical concave and means for driving it, and a conical crushing head within the concave and positioned closely to approach it, and a feed spout adapted to penetrate the smaller end of the concave and extending to a point closely 45 adjacent the cone, and adapted to deliver

material to the space between cone and concave at the front of the cone.

29. A conical crushing mill comprising a rotatably mounted conical concave and means for driving it, and a conical crushing 50 head within the concave and positioned closely to approach it, and means for delivering material to the space between cone and concave at the front of the cone, in relation to the direction of rotation of the 55 cone.

30. A conical crushing mill comprising a rotatably mounted conical concave and a conical crushing head within the concave, 60 and a scraper adapted to clear material from the inner face of said concave along a zone spaced away from and above the crushing zone between the head and the opposed portion of the concave, supporting means for said scraper, said scraper being in rotatable relation with said supporting means, and means for normally holding said scraper blade in scraping position.

31. A conical crushing mill comprising a rotatably mounted conical concave and a 70 conical crushing head within the concave, and a scraper adapted to clear material from the inner face of said concave along a zone spaced away from and above the crushing zone between the head and the opposed portion of the concave, supporting means for said scraper, said scraper being in rotatable relation with said supporting means, and 75 yielding means for normally holding said scraper blade in scraping position.
